UNITED STATES PATENT OFFICE.

JOHN A. LOCK, OF BUFFALO, NEW YORK.

CHIMNEY FLASHING.

Application filed September 17, 1926. Serial No. 136,112.

This invention relates to a chimney flashing adapted to prevent leakage of water through the joint between the roof and the chimney of the building.

It is the object of this invention to provide a flashing of this character which can be made complete and readily assembled with the roof and chimney of the building while erecting the latter, so as to form an absolutely leak-tight joint between the roof and the chimney by so constructing the flashing that an interleaving or intercalating of some members of the flashing and the shingles of the roof is effected, and longitudinal channels are provided on opposite sides of the chimney whereby the water flowing down the roof, will be prevented from entering between the shingles and producing a leak and instead will be conducted away from the shingles and into the above mentioned conductors which latter direct the water to the top of the roof below the chimney, and thereby insure a joint between the roof and the chimney which will exclude the entrance of weather into the building at this point.

In the accompanying drawings:

Figure 1 is a perspective view of a chimney flashing embodying my invention.

Figure 2 is a vertical transverse section showing my improved chimney flashing applied to the roof and chimney of the building, this section being taken on line 2—2, Fig. 3.

Figure 3 is a vertical longitudinal section taken on line 3—3 Fig. 2.

Figure 4 is a vertical section taken on line 4—4 Fig. 2.

Similar characters of reference indicate like parts in the several figures of the drawings.

This improved chimney flashing may be employed between the roofs and chimneys of buildings of various constructions, but as shown in the drawings for example, this chimney flashing is shown in connection with a roof and chimney in which the roof comprises inclined or sloping roof boards 10, and a covering of overlapping shingles 11 applied to the upper side of the roof boards; and the roof being provided with an opening 12 adapted to receive an upright chimney, consisting in this instance of an outer body 13 of bricks which are laid in mortar in the usual way, and a lining 14 arranged within the chimney body and consisting of fire clay or other refractory material.

My improved flashing comprises a base 15 preferably constructed in the form of a rectangular plate, and provided with a central opening, a tubular body rising from this base and consisting preferably of a high front wall 16, a comparatively low rear wall 17, and two longitudinal side walls 18, and two rows of wings 19 arranged on opposite sides of the tubular body, the members of each row lapping one over the other from the uppermost toward the lowermost, and the inner edges of each row of wings being connected with the base 15, adjacent to the respective side wall of the tubular body, while the outer edges of the wings are free and disconnected.

The upper end of the long front wall 16 of the tubular body terminates below or is arranged at a lower horizontal level than the upper edge of the lower rear wall 17 of the tubular body, and the side walls have their upper edges arranged step-fashion, as shown at 20 in Fig. 1. Each of the horizontal edges of the step-shaped upper edges of the side walls 18 are provided with inwardly projecting horizontal flanges 21, and the vertical edges of these step-shaped ends of these walls are provided with vertical flanges 22. The upper edge of the front wall 16 is provided with an inwardly projecting horizontal flange 24, and the upper edge of the rear wall 17 is provided with an inwardly projecting horizontal flange 25.

In the operation of applying this flashing to a building, the same is placed over the roof and around the chimney opening 12 before the chimney is erected, so that the lower end of the base 15 extends over the shingles immediately below the chimney opening 12, as shown in Fig. 3. If desired, this flashing may be retained in this position on the roof by driving one or more nails through the same and into the roof boards, as shown for example by dotted lines 26 in Fig. 2. The shingling of the roof adjacent to the sides and the top of the chimney opening is completed after the flashing has been thus placed upon the roof boards, by continuing the shingling upwardly from the previously shingled part below the chimney opening, so that these shingles extend over the opposite longitudinal edges of the flashing base, and over the upper part thereof which is arranged above the chimney opening.

While applying the shingles over the lon-

gitudinal edge portions of the flashing base and the adjacent parts of the roof boards, these shingles are interleaved or intercalated with the adjacent free end portions of the wings 19, so that each of these wings is arranged between two overlying shingles in the same manner in which shingles lap one over the other. Those shingles of the longitudinal rows which are arranged on the opposite longitudinal sides of the chimney flashing and are intercalated with the respective wings of the flashing, may be secured in place in any suitable manner, for instance, by driving nails through each wing 19 and the shingle immediately below the same, and into the roof board at a point above the lower edge of the next higher shingle and wing of the corresponding row, as shown for example at 27 in Fig. 2, thereby concealing these nails which secure the flashing wings and the adjacent shingles upon the roof board and also preventing the passage of any water through any nail holes which may be formed by such nailing.

In the operation of interleaving the wings of each row with the adjacent shingles, a downward bend is produced at the inner or attached end of each of the wings 19 adjacent to the respective longitudinal wall 18 of the tubular body, as shown at 23 in Figs. 1 and 2, which downward bends of the several wings are lengthwise in line with each other and together form a longitudinal channel, groove or gutter into which the water is directed from the shingles by the wings, so that this water flows to the lower end portion of the base 15 where the same is discharged over the upper surface of the shingles below the chimney opening. By this means, the water is prevented from seeping in between the undersides of the shingles and the top of the roof boards, but instead is shed promptly, thereby preventing leakage at this point into the building between the chimney and the roof.

After the chimney flashing has been thus applied to the roof, the erecting of the chimney proceeds in the ordinary way, and when the same reaches the level of the flange 24 of the long front wall of the tubular body and the adjacent horizontal flanges 21 of the lowermost horizontal edge 20 of the step-shaped upper edge of the side walls 18, then the flanges just referred to are tucked or built into the joint between the two adjacent superposed layers of brick. At the same time, the lowermost vertical flanges 22 of the step-shaped side walls 18 are tucked or built into the adjacent vertical joints between the respective row of bricks. In like manner, the succeeding horizontal flanges 21 and the vertical flanges 22 on the step-shaped edges of the side walls 18 are built into the joints between the succeeding rows of bricks, as the building of

the same by the addition of rows of bricks progresses, including the upper flange 25 of the short rear wall 17, which is in like manner tucked or built into the joint between two superposed rows of bricks.

After this, the building upward of the chimney continues in the usual manner until the desired height is reached. The step formation of the side walls 18 of the tubular body of the flashing is preferably so designed that the same harmonizes with the standard size of bricks in length and height, and thereby enables the flanges 21, 22, 24, 25 to fit in between the horizontal and vertical joints of superposed layers or tiers of brick as they are laid, without requiring any of the bricks to be especially prepared for this purpose, thereby enabling this chimney flashing to be applied to the roof and chimney of the building with the least expenditure of time, whereby the cost is reduced accordingly.

This flashing is preferably constructed of tin or other suitable sheet metal from a plurality of pieces which may be connected with each other in any suitable manner so that in effect, they form one integral structure which has no loose parts liable to become detached, and therefore permits of not only handling the same easily and mounting the same expeditiously on the roof and joining the same with the chimney, but the same also provides a structure which positively seals all the openings in the roof around the chimney, and effectively excludes the passage of rain, snow, dirt and wind under varying weather conditions.

I claim as my invention:

1. A chimney flashing comprising a base plate adapted to be placed over the boards of a roof and having an opening adapted to register with the chimney opening in the roof, a tubular body rising from said base around the opening thereof and adapted to receive the chimney which extends through the roof, and wings arranged on the base to lap one another and adapted to be intercalated with the shingles of the roof.

2. A chimney flashing comprising a base plate adapted to be placed over the boards of a roof and having an opening adapted to register with the chimney opening in the roof, a tubular body rising from said base around the opening thereof and adapted to receive the chimney, which extends through the roof, and rows of wings arranged on said base on opposite sides of said body and the wings in each row having their inner edges next to said body connected with said base while their outer edges are free and lap one another and are adapted to be intercalated with the shingles of the roof.

3. A chimney flashing comprising a base plate adapted to be placed over the boards of a roof and having an opening adapted to

register with the chimney opening in the roof, a tubular body rising from said base around the opening thereof and adapted to receive the chimney which extends through the roof, and rows of wings arranged on said base on opposite sides of said body and the wings in each row having their inner edges next to said body connected with said base while their outer edges are free and 10 lap one another and are adapted to be intercalated with the shingles of the roof, and the wings in each row overlapping one another.

4. A chimney flashing comprising a base 15 plate adapted to be placed over the boards of a roof and having an opening adapted to register with the chimney opening in the

roof, a tubular body rising from said base around the opening thereof, and adapted to receive the chimney which extends through the roof; rows of wings arranged on said base on opposite sides of said body and the wings in each row having their inner edges next to said body connected with said base while their outer edges are free and 20 lap one another and are adapted to be intercalated with the shingles of the roof; the wings in each row overlapping one another, and the inner parts of the wings of both rows being deflected downwardly to form channels on 25 opposite sides of said body.

In testimony whereof I hereby affix my signature.

JOHN A. LOCK.
